US00D868363S

(12) **United States Design Patent** (10) Patent No.: **US D868,363 S**
 Stone (45) Date of Patent: ** *Nov. 26, 2019

(54) **ELECTRONIC CIGARETTE**

- (71) Applicant: **Altria Client Services LLC**,
 Richmond, VA (US)
- (72) Inventor: **Mitchell Stone**, Staffordshire (GB)
- (73) Assignee: **Altria Client Services LLC**,
 Richmond, VA (US)
- (*) Notice: This patent is subject to a terminal disclaimer.
- (**) Term: **15 Years**
- (21) Appl. No.: **29/662,880**
- (22) Filed: **Sep. 10, 2018**

Related U.S. Application Data

- (62) Division of application No. 29/592,200, filed on Jan. 27, 2017, now Pat. No. Des. 829,370.

Primary Examiner — Marissa J Cash*(74) Attorney, Agent, or Firm* — Harness, Dickey & Pierce, P.L.C.(57) **CLAIM**

The ornamental design for an electronic cigarette, as shown and described.

DESCRIPTION

FIG. 1 is a perspective view of an electronic cigarette;
 FIG. 2 is a front view of the electronic cigarette;
 FIG. 3 is a rear view of the electronic cigarette;
 FIG. 4 is a left side view of the electronic cigarette;
 FIG. 5 is a right side view of the electronic cigarette;
 FIG. 6 is a top view of the electronic cigarette; and,
 FIG. 7 is a bottom view of the electronic cigarette.
